MILK BOTTLE

Royden A. Blunt, Baltimore, Md.

Application April 24, 1951, Serial No. 14,942

Term of patent 14 years

(Cl. D58—6)

To all whom it may concern:

Be it known that I, Royden A. Blunt, a citizen of the United States, residing at Baltimore, Maryland, have invented a new, original, and ornamental Design for a Milk Bottle, of which the following is a specification, reference being had to the accompanying drawing, forming a part thereof:

Figure 1 is an elevation of a milk bottle, showing my new design;

Figure 2 is a further elevation of the bottle turned with respect to the position of Figure 1; and

Figure 3 is a top plan view of Figure 1. The dominant features of my design reside in the portions shown in full lines.

I claim:

The ornamental design for a milk bottle, substantially as shown and described.

ROYDEN A. BLUNT.
